UNITED STATES PATENT OFFICE.

FRANK J. BALLINTINE, OF PERTH AMBOY, NEW JERSEY, ASSIGNOR TO THE BARBER ASPHALT COMPANY, OF PHILADELPHIA, PENNSYLVANIA, A CORPORATION OF WEST VIRGINIA.

ROOF COVERING.

Application filed April 6, 1922. Serial No. 550,194.

To all whom it may concern:

Be it known that I, FRANK J. BALLINTINE, a citizen of the United States, residing at Perth Amboy, in the county of Middlesex and State of New Jersey, have invented certain new and useful Improvements in Roof Coverings, whereof the following is a specification, reference being had to the accompanying drawings.

10 This invention relates to roof coverings and more particularly to shingles of the type which are fabricated from fibrous material such as paper, felt, or the like, suitably treated with substances to render said shingles weather-proof and flexible.

An object of the invention is to provide a shingle which is so constructed as to provide means to secure the lower or exposed end of each shingle in such a manner as to cause the same to lay and remain flat against the roof, thus precluding the entrance of rain or snow beneath the shingle ends. This is accomplished in the present invention by providing one or more tongues on each shingle together with a locking flange so that the tongue of an overlapping shingle may engage the flange of an underlying shingle, thus securing together the shingles of adjoining courses. As a result of the construction employed, to be hereinafter more fully set forth, these shingles are caused to simulate very closely the appearance of wooden shingles by reason of the thickened end of each shingle.

35 The above and other objects are accomplished through the preferred embodiments of my invention, illustrated in the accompanying drawings in which:

Fig. I is a view in plain of a fragment of a roof covering consisting of an assemblage of my improved shingles.

Fig. II is a view in perspective of a unit shingle, illustrating more clearly the detail construction.

45 Fig. III is a view in section taken on the line III—III of Fig. I, illustrating the manner in which the shingles are interlocked; and

Fig. IV is a view in plan of a fragment 50 of a roof covering constructed of strips to facilitate the laying of courses, and illustrating a modified form of my invention.

With reference to Figs. I, II and III, 10 55 indicates an oblong shingle of the usual outline and dimensions, constructed of paper,

fiber, or the like, treated with bituminous materials to render the same flexible, non-porous and weather-proof. One end, to constitute the exposed end of the shingle, is folded over to form a locking flange 11 and each of the two side edges of the shingle is formed with a slot 12, which slots extend toward each other, diagonally relative to the edges of the shingle toward the rear or unfolded end. The formation of these slots results in the definition of tabs or spurs 13 wholly within the peripheral confines and directed toward the folded end of the shingle. These shingles 10 are laid in courses in the usual manner and preferably in closely spaced relation as shown in Fig. I, permitting one course to overlap the next and causing each of the flanges 11 of an overlapping course to extend over the adjacent margins to two of the shingles 10 of an underlying course so that their exposed ends present a bond effect. The shingles 10 of one course should be laid relative to those of the next so that the adjacent tabs or spurs 13 of adjacent shingles of an underlying course are seated between the flange 11 and body portion of an overlapping shingle of the next course above. As a result the flanged end 11 of the shingle 10 is held down and compelled to lie flat against the roof at all times. This arrangement of interlocking members is clearly illustrated in Fig. III.

To facilitate the laying of courses these shingles may be fabricated in strips, an expedient frequently adopted. To this end 90 a strip 14 is provided with spaced, transversely extending slots 15, the inner ends of which diverge to define a tongue 16 between said diverging ends. These tongues 16 are the equivalent of a pair of tabs or spurs 13 95 of the first form of shingle when a pair of such shingles are laid in a course. These strips 14 are laid, one overlapping the other, to define the courses of the shingles and to produce a bond effect so that one shingle of an upper course overlaps the adjacent margins of two shingles of a lower course. Each tongue 16 of an underlying course or strip is then introduced between the flange 11 and the body portion of an overlapping shingle 100 of the next course above. It will be noted that in either of these forms the folded ends of the shingles produce a thickened appearance and a roof covered with such shingles 105 resembles very closely a roof covered with 110

the conventional form of wooden shingles which are relatively thick at their exposed ends and taper toward the other ends. Furthermore, the ends of the shingles are reinforced by reason of the fold so as to resist flexing and are thus caused to remain flat against wind pressure, thereby precluding the entrance and accumulation of rain or snow thereunder.

10 Having thus described my invention, I claim:

1. A flexible weather-proof oblong shingle having the lower narrower edge folded under to form a flange with the longer opposed side edges angularly notched to provide downwardly directed locking spurs wholly within the marginal confines thereof, said spurs being adapted to engage between the flange and body portion of an overlapping shingle to hold the flanged end of the latter flat.

2. A covering for buildings embodying rows of flexible weather-proof oblong shingles laid in overlapping courses, each shingle having its narrower exposed end under-folded to provide a flange, an integral downwardly directed locking spur wholly within each side edge of said shingle, said spurs at the adjacent edges of two shingles of an underlying course being inter-engageable upon the flange of an overlapping shingle of the superposed course to hold said flange of the overlapping shingle flat against the surface covered.

3. As a new article of manufacture, an oblong shingle of flexible weather-proof material having the lower end under-folded to provide a flange and each of its side edges formed with an inclined slot, said slots inwardly converging toward the unfolded end of the shingle to define spurs wholly within the marginal confines thereof and downwardly pointed in divergent relation.

4. A roof covering comprising strips of flexible weather-proof material, each strip having one longitudinal edge thereof slotted at uniformly spaced intervals to define a series of oblong shingle ends, each said shingle end having its lower edge under-folded to constitute a flange with the inner end of each slot bifurcated to afford a locking spur, whereby said strips when laid in over-lapping relation form a shingle course with the locking spurs of an under-lying course engaged upon the flanges of an over-lying course.

5. As a new article of manufacture, a strip of flexible weather-proof material having one longitudinal edge formed with transverse slots to define oblong shingle ends with the lower edges thereof under-folded to provide flanges, and the inner end of each said slot bifurcated to define a downwardly directed locking spur.

In testimony whereof, I have hereunto signed my name at Bombay India this third day of March, 1922.

FRANK J. BALLINTINE.
